(57) **CLAIM**

The ornamental design for a container for blood collection, as shown and described.

DESCRIPTION

FIG. 1 is a perspective view of a container for blood component separation and preservation showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is an enlarged fragmentary perspective view thereof, taken along the lines 8-8' shown in FIG. 1;

FIG. 9 is an enlarged fragmentary front elevational view thereof, taken along the lines 9-9' shown in FIG. 2;

FIG. 10 is an enlarged fragmentary top plan view thereof, taken along the lines 10-10' shown in FIG. 6; and,

FIG. 11 is an enlarged fragmentary bottom plan view thereof, taken along the lines 11-11' shown in FIG. 7.

The broken lines showing portions of a container for blood collection are included for the purpose of illustrating environmental structure and form no part of the claimed design.
